UNITED STATES PATENT OFFICE.

JAMES P. HANSON AND JAMES P. CHRISTENSEN, OF CHICAGO, ILLINOIS.

ELECTRIC BURGLAR-ALARM.

SPECIFICATION forming part of Letters Patent No. 292,807, dated February 5, 1884.

Application filed May 10, 1883. (No model.)

To all whom it may concern:

Be it known that we, JAMES P. HANSON and JAMES P. CHRISTENSEN, citizens of the United States of America, residing at Chicago, in the county of Cook and State of Illinois, have invented certain new and useful Improvements in Electric Burglar-Alarms, of which the following is a specification, reference being had therein to the accompanying drawings.

This invention has for its object to produce a device that is connected with the shade or curtain of a window in a manner to set in motion an electric alarm-bell with the removal or pushing aside of such curtain; and it consists of an apparatus secured to the window-frame, and having a vibratable bar provided with spring clamp-jaws, that grasp the edge of the curtain, and held on a central position by a spring-stem to form an incomplete circuit, by wire-connections with a galvanic battery and an alarm-bell, which circuit will be completed by the movement of the curtain in any direction that will release the clamp-bar from its central hold, and will bring it in contact with the internal surface of a surrounding metal rim, all as more fully hereinafter described, and specifically claimed.

In the drawings, Figure 1 represents a perspective view of the apparatus as attached to a window-frame, and Fig. 2 a longitudinal section of the same.

Corresponding letters in the several figures of the drawings designate like parts.

A denotes the base-plate, having two posts, *a* and *a'*, that are tapped for concave-ended screws *b*, which hold between a small mandrel, *c*, having conically-pointed ends that enter the concaved ends of such screws *b*. Upon the center of this mandrel *c* is pivotally secured the slotted middle portion of a bar, *B*, by a pin, *d*, that is passed through holes in the center of such bar *B* and mandrel *c* in a manner that such bar *B* has a free universal vibrating movement between the screws *b* of posts *a*. The forward end of bar *B* has spring-jaws *e*, between which the edge of a curtain is inserted to grasp and hold onto such curtain. The opposite end of bar *B* is concaved, and holds a small rubber cup,

f. Upon plate *A* is secured by a screw, *g*, 50 on a column, *h*, the expanded rim *i* of a tube, *I*, that forms the guide for a stem, *J*, having a collar, *j*, and a head, *K*, and being pushed forward by a spiral spring, *m*. The pointed end of this stem *J*, when inserted into the 55 concaved end of bar *B*, will hold such bar on a central position, and out of contact with the interior surface of rim *i*. The screw *g* and column *h* are insulated from plate *A* by interposing rubber washers *o*. A post, *P*, is 60 secured upon the forward end of plate *A*, and has a screw, *p*, for coupling one of the circuit-wires, *q*, from which the electric current passes through plate *A*, posts *a*, screws *b*, and mandrel *c*, to bar *B*. The other circuit-wire, 65 *r*, is coupled to column *h*, to lead the electric current to tube *I*. This circuit is incomplete as long as the point of stem *J* is engaged with the insulating-cup *f* of the concaved end of bar *B*; but as soon as such bar *B*, by a transverse force, is released from stem *J*, such bar will vibrate, and will come in contact with the internal surface of rim *i*, whereby the electric circuit is completed, and the alarm-bell 70 will ring.

This apparatus, being secured to one side of a window-frame, with its spring-jaws grasping the edge of the curtain, a burglar, in trying to enter the house through the window, and raising or pushing to one side the curtain, will turn the bar *B* away from its central hold, and will thus connect the electric circuit to ring the electric bell, that will rouse the inhabitants.

This device is simple in its construction, 85 and reliable in its operation, and with a slight change it can as well be applied to inside blinds, or to announce the opening of a window.

What we claim is—

1. In an electric burglar-alarm provided with suitable circuit-connections, the bar *B*, universally pivoted between posts *a* *a'* of plate *A*, and having insulating-cup *f*, in combination with tube *I*, insulated from plate *A*, and 95 having expanded rim *i* and spring-stem *J*, all substantially as described, to operate as specified.

2. In an electric burglar-alarm provided with suitable circuit-connections, the bar B, universally pivoted between posts *a a'* of plate A, having spring-jaws *e* and insulating-cup *f*, in combination with tube I, insulated from plate A, and having expanded rim *i* and spring-stem J, all substantially as and for the purpose described, to operate as specified.

In testimony whereof we affix our signatures in presence of two witnesses.

JAMES P. HANSON.
JAMES P. CHRISTENSEN.
